2 SHEETS—SHEET 2.

UNITED STATES PATENT OFFICE.

JOHN FRANCIS CONNELL, OF LOS ANGELES, CALIFORNIA.

DEVICE FOR OPENING, CLOSING, AND LOCKING DOORS.

No. 851,616.

Specification of Letters Patent.

Patented April 23, 1907.

Original application filed April 2, 1906, Serial No. 309,503. Divided and this application filed July 30, 1906. Serial No. 328,460.

To all whom it may concern:

Be it known that I, JOHN FRANCIS CONNELL, of the city of Los Angeles, in the county of Los Angeles and State of California, have invented certain new and useful Improvements in Devices for Opening, Clos-

ing, and Locking Doors, (my said device being more especially applicable to the doors of elevator shafts and other inclosures,) of which the following is a full, clear, and exact description or specification, reference being had to the accompanying drawings and to the figures and letters marked thereon.

In Letters Patent previously granted to me, the said JOHN FRANCIS CONNELL, numbered 773,531, dated October 25th, 1904, the device comprised under the Letters Patent has its operative parts connected to two sliding doors and to each other by means of bolts or rivets, and pivotal connections, which as shown in the drawings and described in the specification of the aforesaid Letters Patent, are neither capable of adjustment nor adapted for taking up any slackness in the joints of said parts which from time to time naturally results from practical wear and tear in the use of the device, nor is there provision in the operating lever and link of the said device for maintaining the operating lever and link rigidly stiff, and horizontal by interlocking of the said lever and the link, when the lever and link are in the horizontal position.

My present improvements have for their object to provide for interlocking the operating lever and the two links connecting the said lever to the two sliding doors, and to the spring or equivalent device whereby the two sliding doors, operating lever and links, are connected to one side, end or angle of the elevator inclosure, and to maintain the said operating lever and links rigidly locked when the two doors are closed over the opening of the elevator inclosure into the cage operating therein.

My invention has also for its object to provide adjustable pivotal connections for the aforesaid operating lever and links and their connections, by which they are at all times capable of adjustment corresponding with the wear and tear of the joints themselves.

My invention has also for its object to enable the adjacent edges of the two sliding doors in the elevator inclosure to be brought much nearer to the corner of the inclosure whereinto and toward which corner the

doors slide when the doors are opened than is possible by or with the spring connection projecting from the corner of the inclosure, and of the kind described in the specification and shown in the drawings of my aforesaid Letters Patent.

Upon the annexed drawings Figure 1, is an elevation of one side of the interior of an elevator inclosure at the part thereof where two sliding doors are situated, which on being opened admit of ingress or egress to or from the elevator cage or car, operating within the inclosure, and when closed prevent such ingress or egress. Fig. 2, is an end elevation corresponding to Fig. 1. Fig. 3, is a horizontal section on the line *a*, *a*, Fig. 1, and part plan showing the two sliding doors closed. Fig. 4, is a corresponding horizontal section and part plan showing the two sliding doors in the open position. Fig. 5, is a side elevation upon a larger scale showing the coupling box and spring device whereby the opening, closing and locking, link and lever parts of the device, are elastically connected to that part of the elevator inclosure adjacent to which the doors become situated when the said doors are open. Fig. 6, is a vertical section corresponding to Fig. 5. Fig. 7, is a transverse section corresponding to Figs. 5 and 6, in all respects excepting that the spiral spring is dispensed with. Fig. 8, is a front elevation of the coupling box on a scale corresponding to Figs. 5, 6, and 7, showing the opening therein and the end link partly in elevation and partly in vertical section, also the attachment and adjusting parts of the device within the box. Fig. 9, is a horizontal section upon the line *a*, *a*, Figs. 5, and 6. Fig. 10, is a transverse vertical section of the box, but wherein the lugs for fastening it to the corner or to a column, or to the grille work of the elevator inclosure are shown at one side of the box instead of in the front thereof as in Figs. 5, 6, 7, 8, and 9. Fig. 11, is an enlarged view of the block, which is connected to one edge of the sliding door, and on which one of the links of the manually operated lever of the device is pivoted. Fig. 12, is a part horizontal section on the line *b*, *b*, Fig. 11. Fig. 13, is an elevation on the same enlarged scale as Fig. 11, of the lifter and upward projection of the operating lever. Fig. 14, is a vertical section on the line *c*, *c*, Fig. 13, showing the india rubber pad within the projection and lifter whereby the operating of the device is effected as hereinafter de-

scribed. Fig. 15, is a transverse section on the line q, q , Figs. 1, and 3, of the outer link showing the india rubber pad within the projection which presses upon the under edge of the operating lever when in the locked position. Fig. 16, is a side elevation of that end of the link of the opening and closing device which connects with the box of the apparatus, fastened into the framing or grille work, corner or column of the elevator inclosure. Fig. 17, is a transverse section on the line p, p , Fig. 16, showing the ends of the screws each entering into the countersunk hole at each side of this fastened part of the link. Fig. 18, is a plan corresponding to Fig. 13. Fig. 19, is a section of the joint on the line n, n , Fig. 13.

In Figs. 1, to 4, such parts of the elevator inclosure as are essential to illustrate my invention are marked A. The two elevator doors are marked B, and B', respectively, while the panel over which they close when the doorway in the elevator inclosure is open for the purposes of ingress to and egress from the elevator cage or car being had, is marked C, Figs. 1, 3, and 4. The doors B, and B', are carried upon the horizontal rails E, and F, respectively, by the anti-friction rollers G⁵, connected by roller blocks H, to the upper edge of each of the doors B, and B'. In Fig. 1, the doors B, and B', are shown in the closed position, and the opening and closing lever J, and links I, and K, are also shown in full lines closed, that is to say, in the horizontal position of the said lever J, and links I, and K, being also shown in the half opened position of the doors B, and B', in dotted lines. The lever J, is pivoted to the door B', by the pivot h, in Fig. 1, and it is connected to the door B, by the link K, and the left hand part of the lever J, is long enough so that when in the horizontal position its thumb and finger piece L, closes down upon the upper edge of the link K, and maintains all parts of the opening and closing device in the horizontal position. The lever J, is connected by the pivot j, Fig. 1, to the link I, the outer end of which is fastened to the pivot H⁶, of the spring bolt H², contained in the box G, all as shown at Fig. 1. The left hand end of the link I, is formed as a catch N, which engages with the under edge of the lever J, when the opening, closing and locking device is in the horizontal position shown in Figs. 1, and 3. Both the thumb and finger piece L, and the catch N, are provided with a lining of india rubber as shown in the enlarged sections Figs. 14, and 15, to take up as far as possible any blow or shock which may be due to the closing of the lever J, and the links K, and I, into the horizontal and locked position. At Figs. 14, and 15, the enlarged sections respectively, of these parts of the device, the india rubber pads O, are shown in section as held in the parts L, and

N, by means of wood screws N', passed through a countersunk hole in each of the parts L, and N, through which holes the thread portions of the screw enter the india rubber or elastic pads O, and firmly secure the pads O, in their places. 70

As shown enlarged to about its actual size at Figs. 5, and 6, the spring attachment whereby the link I, in Figs. 1, and 3, is attached elastically to the framing or grille work of an elevator inclosure, consists of the box G, formed with an upper and lower projection G², and G³, respectively, through which holes g', are made for the passing of bolts or screws for securely connecting the box G, 80 with the framing or grille work of the elevator inclosure. Through the rear or back of this box marked G⁴, in Figs. 5, 6, and 8, an opening is made through which the head portion of the bolt H², passes as more particularly 85 shown in section in Fig. 4. The head or that portion of this bolt H², which is situated within the hollow of the box G, is constructed as having two eye pieces H³, and H⁴, respectively, as particularly shown at Figs. 6, and 7, between which the end of the lever F, is situated, and held in place therein by the two conically pointed screws H⁵, and H⁶, which pass through these screwed holes in the eye pieces H³, and H⁴. The conically 90 pointed screws H⁵, and H⁶, have a screw driver slot cut into the outer extremity of each so that a screw driver, having its screw turning member at the side of the shank of the screw driver can be passed into either 100 side of the box G, and inserted into the slot of either screw, H⁵, and H⁶, for the purpose of turning the screw in the eye pieces H³, and H⁴, until the proper adjustment of the conical points of the screws H⁵, and H⁶, 105 within the corresponding conical holes in the end of the lever F, is brought about so as to insure steady, smooth and non-shaking operation of the lever F, upon the pivots constituted of the conical points of 110 the screws H⁵, and H⁶. Upon each of the screws H⁵, and H⁶, a lock nut H⁷, and H⁸, respectively, are carried so that after the screws H⁵, and H⁶, have been properly adjusted they are maintained in their adjusted 115 positions by applying a wrench to tighten the two lock nuts H⁷, and H⁸. The outer end of the bolt H², has a screw thread cut upon it, and upon this screw thread the nut H⁹, is carried. A spiral spring H¹⁰, is also 120 carried on that part of the bolt H², situated between the box G, and the nut H⁹, and by tightening the nut H⁹, to any required extent the compression of the spring H¹⁰, is effected, so as to operate elastically when the 125 act of opening or closing the door shown at Figs. 1, and 2, of the drawings, is terminated, thus cushioning any blow, percussion or jar which may take place on the termination of either of these movements of the doors. 130

Instead, however, of using the spiral spring H^{10} , for the purpose of cushioning the blow due to the opening or closing of the elevator inclosure doors, the cushion effect may sometimes be dispensed with, and in this case I secure the bolt H^2 , into the rear part of the box H , without using the spring H^{10} , as shown at Fig. 5, wherein the bolt H^2 , has a shorter shank than in Figs. 3, and 4, and is rigidly held in the rear part G^1 , of the box G , by the screw nut H^{11} , which is tightened thereon by a wrench in the ordinary manner. When the box G , cannot be conveniently attached to the framing or grille work of the elevator inclosure by means of the upper and lower projections G^2 , and G^3 , at the front of the box G , as shown in Figs. 5, 6, and 7, then corresponding lugs are or may be placed at one of the lateral faces of the box G , as shown in Fig. 8, in which case the screws or bolts are passed through holes in these lateral lugs instead of through the holes g' , and g' , shown in Fig. 6.

As shown by the larger views Figs. 11 and 12, the front end of the lever J , in Figs. 1, and 3, is attached to the link K , and the link K , is attached to the pivotal piece K' , at the edge of the elevator door, by means of a screw K^2 , having a conical head as shown more especially in section in Fig. 12. The shank of this screw K^2 , is passed into the corresponding screw hole in the part K' , and has a lock nut K^4 , at the inner end thereof. The object of placing the screw K^2 , with conical head, and lock nut K^4 , to retain the link K , at this point of connection, is to enable adjustment thereof to be made and retained when any looseness of the lever J , about the bolt j , may take place by wear or tear; in which condition any looseness due to this wear and tear is removed by turning the screw K , by applying a screw driver in the slot of the head thereof and tightening the nut K^4 , correspondingly. The other end of the lever J , as shown enlarged at Figs. 11, and 13, not only shows the thumb piece L , having its india rubber cushion as in contact with the upper edge of the link K , when the opening and closing and locking device is in the horizontal position, but it also shows the outer end of the joint by which the lever J , is connected to the link K , as shown on the smaller scale at Figs. 1, and 2. A section of this joint on the line n , n , is shown at Fig. 19. A washer E' , is situated between the parts K , and J , at this joint so that the lever J , and link K , do not touch each other, but are kept apart by the washer E' . Through the lever J , and link K , and the washer E' , is a circular hole through which the screw E^2 , is passed. It will be noticed that the screw E^2 , is constructed with a conical head, and that a conical washer E^3 , is in the lever J . By tightening the screw E^2 , into the tapped hole in the washer E^3 , both the conical head

of the screw E^2 , and conical edge of the washer E^3 , are drawn tightly together, so that the link K , and lever J , respectively, are capable of being adjusted to any required degree of accurate fitting and movement together, and should any wear or tear or looseness take place in these parts the said joints are or may be at any time tightened by applying a screw driver to the slot therefor in the conical head of the screw E^2 . By turning the screw driver, the screw E^2 , is tightened in the washer E^3 . For the purpose of maintaining the screw E^2 , the washer E^3 , the lever J , and link K , in proper operative relationship, a lock nut E^4 , is applied to the outer end of the screw E^2 , by which arrangement the operative parts of the joints are capable at all times of being maintained in complete working condition without looseness, shake or noise. 85

I claim as my invention.

1. The device for operating two doors capable of sliding parallel to each other and so as to open, close and lock the same when closed, consisting of an operating lever pivoted to the edge of one of the sliding doors, and connected movably by a pivoted link to the edge of the other sliding door, the end of the lever connected to the two sliding doors having an upwardly projecting stop containing an elastic body which closes down upon the outer edge of the link which connects the operating lever to the outer sliding door, the opposite end of the operating lever being connected to another link whose outer end is attached by pivotal connections to the elevator inclosure, and whose end movably connected to the operating lever is constructed with an upwardly operating stop provided with an elastic body which closes against the under edge of the operating lever simultaneously with the closing of the stop at the other end of the operating lever against the upper end of the link which connects the operating lever with the outer door, substantially as hereinbefore described. 100

2. The device for operating two doors capable of sliding parallel to each other and so as to open, close and lock the same when closed, consisting of an operating lever pivoted to the edge of one of the sliding doors, and connected movably by a pivoted link to the edge of the other sliding door, the end of the lever connected to the two sliding doors having an upwardly projecting stop containing an elastic body which closes down upon the outer edge of the link which connects the operating lever to the outer sliding door, the opposite end of the operating lever being connected to another link whose outer end is attached by pivotal connections to the elevator inclosure, and whose end movably connected to the operating lever is constructed with an upwardly operating stop provided with an elastic body which closes against the 115

120

125

130

under edge of the operating lever simultaneously with the closing of the stop at the other end of the operating lever against the upper end of the link which connects the operating lever with the outer door, the pivotal connection of the operating lever with one sliding door, and the connection of the link with the other sliding door, the connection of the outer end of the operating lever with the outer link and the pivotal connection of the outer end of the outer link with the ele-

vator inclosure being adjustable, substantially as hereinbefore described.

In testimony whereof, I have hereunto set my hand and seal, at the city of Los Angeles, 15 aforesaid, in the presence of two subscribing witnesses.

JOHN FRANCIS CONNELL. [L. S.]

Witnesses.
